UNITED STATES PATENT OFFICE

LEO J. ROUSSEAU, OF DETROIT, MICHIGAN, ASSIGNOR OF ONE-THIRD TO LEO J. ROUSSEAU, ONE-THIRD TO ERNEST J. ROUSSEAU, AND ONE-THIRD TO RANOL J. ROUSSEAU, ALL OF DETROIT, MICHIGAN

DESIGN FOR A TOY SEESAW

Application filed September 13, 1929. Serial No. 32,832. Term of patent 3½ years.

To all whom it may concern:

Be it known that I, LEO J. ROUSSEAU, a citizen of the United States, residing at Detroit, in the county of Wayne and State of Michigan, have invented a new, original, and ornamental Design for a Toy Seesaw, of which the following is a specification, reference being had to the accompanying drawing, forming part thereof.

The figure is a perspective view of a toy see-saw, showing my new design.

I claim:

The ornamental design for a toy see-saw, as shown.

LEO J. ROUSSEAU.
